UNITED STATES PATENT OFFICE.

JOHN W. PARKER, OF COLUMBUS, OHIO.

PUZZLE.

964,688.

Specification of Letters Patent. Patented July 19, 1910.

Application filed January 20, 1910. Serial No. 539,119. (Model.)

To all whom it may concern:

Be it known that I, JOHN W. PARKER, a citizen of the United States, residing at Columbus, in the county of Franklin and State of Ohio, have invented certain new and useful Improvements in Puzzles; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in puzzles and comprises a simple and efficient device of this nature having various details of construction and combinations and arrangements of parts 20 which will be hereinafter fully described and then specifically defined in the appended claims.

I illustrate my invention in the accompanying drawings in which the various steps 25 of the puzzle are illustrated by different views in which:-

Figure 1 shows the two coils of wire in their proper relative positions separated and about to be interlocked. Fig. 1^a designates the first step in solving the puzzle. Fig. 2 is an edge elevation showing the second step in accomplishing the puzzle. Fig. 3 is a side elevation of the parts assuming the positions shown in Fig. 2. Fig. 4 is a 35 detail view showing the two coils moved relative to each other nearly one revolution, third step. Fig. 5 illustrates the parts assuming the fourth step in accomplishing the puzzle. Fig. 6 designates the fifth step in 40 accomplishing the puzzle, and Figs. 7 to 16 the various steps that the two coils assume in completing the puzzle, the reverse movements of each step being repeated to disconnect the two coils from each other.

45 Reference now being had to the details of the drawings by letter, A designates one of the wires which has its two ends B and C bent in circular form and spaced apart a slight distance, the two ends having a short bridge piece D holding the same spaced apart and each end is slightly grooved as at D' for a purpose which will be hereinafter described. Said arm is bent to form the two irregular shaped loops E and E', the latter 55 of which is connected by a small bridge F to one end of the wire, the loops E and E'

being preferably in the plane in which the curved end B is disposed, while a loop H is formed in a plane at right angles to the plane of the coil and is thence bent upon 60 itself forming a loop I, one arm of which loop I merges into the loop E', as shown clearly in Fig. 1 of the drawings. The second wire, designated by letter K, is turned to form a coil, one end of the wire being bent 65 to form the loop L, the end N of which is disposed parallel to the end O, as shown clearly in Fig. 1 of the drawings, the loop L being at right angles to the plane of the coil K.

In accomplishing the puzzle, the operator 70 holds one wire in each hand, places the end O in under the ends B and C, as shown in Fig. 1^a of the drawings, after which the end O of the wire K is inserted through the loop E' with the end N of the wire 75 sliding in the grooves D' and upon the bridge F connecting the ends, as shown in Figs. 2 and 3 of the drawings, after which the two coils thus interlocked are given nearly a complete revolution until the end 80 N comes opposite the loop H, the parts assuming the position shown in Fig. 4 of the drawings. A further rotary movement of the two coils in the same direction will bring the parts to assume the position shown in 85 Fig. 5 of the drawings in which the right angled loop L will be positioned opposite the space designated in Fig. 1 by letter Q and which represents the neck portion entering the right angled loop H. The coil 90 K is then moved so that the loop E will partially extend through the loop L and in which the circular shank portion of the coil K will be positioned as shown opposite the opening Q at the entrance of the loop H. 95 The two wires forming the coils are then reversed to assume the positions shown in Fig. 7 of the drawings in which positions the coil K passes through the loop H and the two loops E and L interlock. 100

In Fig. 8 of the drawings, the coil K is shown as being turned to the left with the adjacent portions of the coil K at the entrance of the loop L bearing against the wire forming the coils E and E' at points diametrically opposite. The next step in the accomplishment of the puzzle and which is illustrated in Fig. 9 of the drawings shows the end O of the coil K inserted through the loop H with the two loops B 110 and L interlocking as shown. The next step, as shown in Fig. 10, illustrates the two

coils with the loop II as drawn through between the two ends O and N of the coil K and in Fig. 11 the coil K has been moved laterally, showing the loop L as interlocking with the loop E of the coil A. In Fig. 12, a half revolution has been imparted to the coil K to bring the parts as shown with the two loops L and E interlocking and the two coils positioned in parallel planes. In Fig. 13 of the drawings, the coil A assumes the same position as shown in Fig. 11, but the coil K has been turned rearward with the point O brought in contact with the grooves D' and the ends of the wire forming the coil 15 A and moves slightly by the bridge connecting said ends. In Fig. 14 the two loops E' and L are shown as interlocking each other at nearly right angles and in Fig. 15 the loop L is shown as having been passed 20 through the neck or space Q leading to the loop H, the two loops H and L interlocking at substantially right angles to each other. In Fig. 16 the two coils are shown one above the other in planes at right angles to each 25 other with the two coils H and L interlocking and at right angles to each other. The parts being thus connected together, similar reverse movements as described and imparted to the two coils will separate the two 30 wires or coils one from the other.

What I claim to be new is:—

1. A puzzle comprising two wires, each bent into a coil, one of said wires being bent to form a loop at right angles to the plane of the coil and the other wire having a plurality of loops disposed in planes at right angles to each other, and a bridge connecting the ends of one wire and holding the same spaced apart a slight distance.
- 40 2. A puzzle comprising two wires, each bent into a coil, one of said wires being bent to form a loop at right angles to the plane of the coil and the other wire having a plurality of loops disposed in planes at right angles to each other, a bridge connecting the ends of one wire and holding the same spaced apart a slight distance, one of said plurality of loops having direct connection with one end of the wire upon which it is bent.
- 50 3. A puzzle comprising two wires, each bent into a coil, one of said wires being bent to form a loop at right angles to the plane of the coil and the other wire having a plurality of loops disposed in planes at right angles to each other, a bridge connecting the ends of one wire and holding the same spaced apart a slight distance, one of said plurality of loops having direct connection

with one end of the wire upon which it is bent, the two ends connected by said bridge being slightly grooved longitudinally.

4. A puzzle comprising two wires, each bent into a coil, one of said wires being bent to form a loop at right angles to the plane of the coil and the other wire having a plurality of loops, one of which is at right angles to the plane of the coil of which it is an integral part, and others formed in alignment with the latter.

5. A puzzle comprising two wires, each bent into a coil, one of said wires being bent to form a loop at right angles to the plane of the coil and the other wire having a plurality of loops, one of which is at right angles to the plane of the coil of which it is an integral part and others formed in alignment with the latter, and an irregular outlined loop connecting the two loops, one at right angles to and the other in alignment with the coil.

6. A puzzle comprising two wires, each of which is bent to form a coil, one of said coils having a loop at right angles to the plane thereof with the ends of the wire forming the same parallel to each other and spaced apart, the other wire bent to form two loops which are at right angles to the coil of which they are an integral part, thence bent to form a plurality of loops which are in a plane coincident with the plane of one of the wires forming the coil of the second referred to wire, and a bridge connecting one of said plurality of loops with one end of the wire of which it is a part.

7. A puzzle comprising two wires, each of which is bent to form a coil, one of said coils having a loop at right angles to the plane thereof with the ends of the wire forming the same parallel to each other and spaced apart, the other wire bent to form two loops which are at right angles to the coil of which they are an integral part, thence bent to form a plurality of loops which are in a plane coincident with the plane of one of the wires forming the coil of the second referred to wire, the two ends of the wire having said plurality of loops terminating opposite each other, and a bridge connecting the same and grooved longitudinally serving as a guide means.

In testimony whereof I hereunto affix my signature in the presence of two witnesses.

JOHN W. PARKER.
